UNITED STATES PATENT OFFICE.

WALTER HERBERT SMITH, OF WILKINSBURG, PENNSYLVANIA, ASSIGNOR TO WESTINGHOUSE ELECTRIC & MANUFACTURING COMPANY, A CORPORATION OF PENNSYLVANIA.

CONTROL APPARATUS.

Application filed February 19, 1921. Serial No. 446,300.

To all whom it may concern:

Be it known that I, WALTER HERBERT SMITH, a citizen of the United States, and a resident of Wilkinsburg, in the county of 5 Allegheny and State of Pennsylvania, have invented a new and useful Improvement in Control Apparatus, of which the following is a specification.

My invention relates to control apparatus and particularly to apparatus employed in connection with the control of electric railway motors and the like.

The object of my invention is to provide a relay to be remotely controlled for 15 governing the acceleration of a motor independently of the usual current-limiting device.

My invention will be described in connection with the accompanying drawings in 20 which—

Figure 1 is a view of apparatus embodying my invention.

Fig. 2 is a side view partially in elevation and partially in section, of a relay 25 constructed in accordance with my invention.

Fig. 3 is a front view of the armature actuated by one of the relay magnets.

Fig. 4 is a diagrammatic view of 30 circuits and apparatus embodying my invention.

Fig. 5 is a sequence chart indicating the order of closure of the various contactors.

Referring to Figures 1 and 2, a relay 1 35 is provided with a member 2 which is pivotally mounted upon a frame 3 and is biased by a spring 4 in such manner as to be normally disengaged from a magnet 5. Contact members 6 and 7 are mounted on opposite ends of member 2. The contact member 6 coacts with a stationary contact member 8 in the normal or biased position of member 2. An armature member 9, pivotally mounted upon the frame 3, carries a 40 contact member 11 and is controlled by a magnet 12. The magnetizing force of the magnet 12 is applied through a core member 13 that extends diagonally toward the armature member 9. The magnetizing force 45 of the magnet 5 is applied through a core member 14 to an armature 15 of substantially L-shape that is secured to the member 2.

A current-limiting relay of well-known

type, having a coil 16, plunger 17, and 55 contact members 18 and 19, for convenience, is mounted above the previously described relay structure and is, in part, supported thereby.

The operation of the relay may be set 60 forth as follows:

The energization of magnet 12 actuates armature 9 upwardly and effects the engagement of contact members 7 and 11. The energization of magnet 5 attracts the armature 15, carrying with it member 2 and effecting the disengagement of contact members 6 and 8. Contact members 7 and 11, and contact members 6 and 8 are disengaged simultaneously by the movement of the 70 pivotally mounted member 2, the contact member 7 moving inwardly out of the path of movement of the contact member 11, as will be readily understood. The contact member 11 engages the inclined surface of 75 the adjacent end of the member 2.

Assuming that magnet 5 is thereafter demagnetized, the member 2, which tends to restore the engagement of contact members 6 and 8, is restrained so long as magnet 5 remains energized, and contact member 11 yieldingly engages member 2, restraining the latter from resuming its normal position.

When magnet 12 is de-energized, the several contact members resume their respective normal positions in which they are illustrated.

Referring to Fig. 4, the application of my invention will be described in connection with a system of railway control. A motor 21 is connected in circuit with a starting resistor 22 and, through a line contactor 23, to positive line conductor 24. The motor is connected to ground through a 95 conductor 25 and the actuating coil 16 of a current-limiting relay 26.

A well-known type of master controller 27 is employed to establish a circuit for the line contactor 23, and other circuits are 100 completed by a sequence controller 28.

The sequence controller 28 is actuated, in a well-known manner, by an electrically-controlled pneumatically-operated mechanism having magnetically-controlled operating valves which are actuated by the coils "On" and "Off". In the initial position of 105 the sequence controller, the "On" and "Off"

coils are de-energized. The concurrent energization of both coils actuates the drum members of the controller to the left. De-energization of the "Off" coil arrests the progress of the sequence drum, and de-energization of both "On" and "Off" coils causes the drum to be returned to its normal or initial position.

A push-button switch 29, in conjunction with the sequence controller, controls the magnets for operating the relay 1.

Assuming that the various parts of the apparatus occupy the positions illustrated in Fig. 4, the operation of the system will be set forth as follows:

Upon the movement of the master controller 27 to its first operative position "A," a circuit which is established for the coil 31 of the line contactor 23, extends from positive conductor 32, through contact members 33, 34 and 35, conductors 36 and 37, coil 31, conductor 38, and contact members 39, 40 and 41 to negative conductor 42. The line contactor 23 closes to complete a main motor circuit extending from line conductor 24, through contactor 23, resistor 22, motor 21, conductor 25 and coil 16, to ground. An interlock 43, connected to line contactor 23 completes a circuit which extends from positive conductor 32 through contact members 33, 34 and 35, conductor 36, conductor 44, the "On" coil, conductor 45, interlock 43, conductor 38 and contact members 39, 41 and 42 to negative conductor 43. If the "Off" coil remains de-energized, there is no movement of the sequence controller.

The actuation of master controller 27 to its second operative position "B" establishes a circuit for the "Off" coil extending from positive conductor 32 through contact members 33, 34 and 46, conductor 47, contact members 48, 49 and 51, conductor 52, contact members 8 and 6, conductor 53, relay 26, conductor 54, the "Off" coil, conductor 55, interlock 50, conductor 38 and contact members 39, 40 and 41, to negative conductor 42.

The sequence drum is actuated to the left, progressively energizing the coils of accelerating contactors 56, 57 and 58, in a familiar manner, to shunt resistor 22 and accelerate the motor 21.

In the acceleration of the motor under load, as, for example, in the case of a railway car starting up a heavy grade, if the load current is sufficiently high to actuate relay 26, the circuit for the "Off" coil, as traced, will be interrupted and the progression of the sequence drum arrested. The operator may advance the sequence drum one step by actuating push-button switch 29, establishing a circuit for the coil 59 of relay magnet 12, extending from positive conductor 32, through push button 29, conductor 61, coil 59, conductor 62, conductor 38, and

contact members 39, 40 and 41, to negative conductor 42. Contact member 11 is actuated to engage contact member 7. A circuit is established for the "Off" coil of the sequence controller, extending from positive conductor 32, through contact members 33, 34 and 46, conductor 47, contact members 48, 49 and 51, conductor 52, contact members 8, 6, 7 and 11, conductors 63 and 54, the "Off" coil, conductor 55, interlock 50, conductor 38 and contact members 39, 40 and 41, to negative conductor 42.

Assuming that the progress of the sequence drum was arrested in position *b* and, since it has been continued by the actuation of push button switch 29, contact member 64 engages contact members 65 and 66 in the intermediate position between positions *b* and *c*. A circuit is now established from positive conductor 32, contact members 33, 34 and 35, conductor 36, contact members 66, 64 and 65, conductor 67, conductor 68, coil 69 of magnet 5, conductors 62 and 38, and contact members 39, 40 and 41 to negative conductor 42. Member 2 is now actuated from its biased position to disengage contact members 6 and 8, again interrupting a circuit for the "Off" sequence coil previously traced.

Contact member 11 moves upwardly, interlocking with member 2, as previously described. During the engagement of contact members 64, 65 and 66, a shunt circuit is established, extending from conductor 32 through contact members 33, 34 and 35, conductor 36, contact members 66, 64 and 65, conductors 67, 63 and 54, "Off" coil, conductor 55, interlock 50, conductor 38 and contact members 39, 40 and 41 to negative conductor 42. The "Off" coil is not de-energized until the sequence controller has been actuated substantially to position *c*, disengaging contact members 64 and 65.

The sequence controller may be advanced to position *d* by again momentarily actuating the push button 29. It will be noted that, when the sequence controller is advanced one step for each operation of the push-button switch there is, of course, a predetermined time interval between the steps determined by the pneumatically-operated actuating mechanism. The motor is accelerated in the manner previously described and at a predetermined safe rate, in cases of emergency, independently of the current-limiting device.

Upon returning the master controller 27 to its "Off" position, the main circuit is interrupted by the opening of line contactor 23, and the sequence controller is returned to its initial position since the "On" and "Off" coils are de-energized upon the opening of the line contactor.

The relay, as described, provides for simple and effective means for manual control

of the acceleration of a motor in case of emergency. It is not possible to actuate the sequence controller more than one step at a time since the relay cannot be restored to its initial condition except upon release of the push-button switch and the progression of the sequence drum to the next successive position. Actuation of the sequence controller and the rate of acceleration of the motor is fixed by the pneumatically operated mechanism in conjunction with the manual control of the push button.

I claim as my invention:—

1. The combination with a plurality of pairs of relatively movable contact members, two of said contact members being simultaneously movable, of means for selectively effecting the engagement of one or a plurality of said pairs of contact members and electro-responsive means for effecting the disengagement of all the said pairs of contact members.

2. The combination with a plurality of pairs of relatively movable contact members, two of said contact members being simultaneously movable, of electro-responsive means for selectively effecting the engagement of one or a plurality of said pairs of contact members and electro-responsive means for effecting the disengagement of all the said pairs of contact members.

3. The combination with a plurality of pairs of relatively movable contact members, two of said contact members being mechanically connected and one of said pairs of contact members being normally in engagement, of electro-responsive means for disengaging one of said pairs of contacts, and electro-responsive means for effecting the engagement of one of said pairs of contact members, comprising one of said mechanically connected contact members, without effecting the disengagement of said normally-engaged contact members.

4. The combination with a plurality of pairs of relatively movable contact members, two of said contact members being mechanically connected and one of said pairs of contact members being normally in engagement, of electro-responsive means for effecting the engagement of one of said pairs of contact members, comprising one of said

mechanically connected contact members, without effecting the disengagement of said normally-engaged contact members, and electro-responsive means for effecting the disengagement of all the said pairs of contact members.

5. The combination with a pivotally mounted member, and two contact members mounted thereon, of a stationary contact member normally in engagement with one of said contact members, a movable contact member for engaging the other of said contact members, and electro-responsive means for simultaneously effecting the disengagement of all of said contact members.

6. The combination with a pivotally mounted member, and two contact members mounted thereon, of a stationary contact member normally in engagement with one of said contact members, a movable contact member for engaging the other of said contact members, electro-responsive means for actuating said movable contact member, and electro-responsive means for simultaneously effecting the disengagement of all of said contact members.

7. The combination with two pairs of coacting contact members and a single movable member for carrying one member of each pair of contact members, of an electromagnet for actuating said movable member to disengage one pair of said contact members, and a second electromagnet for effecting the engagement of the second pair of contact members when the movable member is in a predetermined position.

8. The combination with a plurality of pairs of coacting contact members and a single movable member for carrying one member of each of said pairs of contact members, of an electromagnet for actuating one of the other contact members into engagement with the coacting contact members carried by said movable member when the latter occupies its normal position, and a second electromagnet for controlling the position of said movable member to control the engagement of both of said pairs of contact members.

In testimony whereof, I have hereunto subscribed my name this 8th day of February, 1921.

WALTER HERBERT SMITH.
